(57) **CLAIM**

The ornamental design for a watch, as shown and described.

DESCRIPTION

Fig. 1.1 is a top view;

Fig. 1.2 is a bottom view;

Fig. 1.3 is a left side view;

Fig. 1.4 is a right side view;

Fig. 1.5 is a front view; and

Fig. 1.6 is a back view.

Broken lines in the drawings represent parts of the watch, which form no part of the claimed design.
